GAME BOARD

Filed Sept. 24, 1927

UNITED STATES PATENT OFFICE.

HARRY SCHLESINGER, OF PASSAIC, NEW JERSEY.

GAME BOARD.

Application filed September 24, 1927. Serial No 221,695.

This invention relates to improvements in games, particularly in game boards, and it is the principal object of my invention to provide a board having a plurality of numbered 5 depressions closed at the bottom and adapted to receive a ball propelled by means of a cue as in the customary billiard games.

Another object of my invention is the provision of a game-board equipped with means 10 for exchanging one or the other of the numbered depressions for repair or for a change in numbers, etc.

A further object of my invention is the provision of a game-board which is adapted to 15 be placed on an ordinary pool table or the like and if so used is equipped with means for preventing a straying of the balls into the pocket of the billiard table.

A still further object of my invention is 20 the provision of a novel and improved game-board in which the means for preventing a straying of the balls are made removable, and a board which allows the playing of a great and varied number of games, as for instance 25 billiards, ball games in which in the manner of the ordinary pool game in which the player whose ball marked with the highest number, and entering the pocket marked by the highest number is considered the winner.

30 These and other objects of my invention will become more fully apparent as the description thereof proceeds, and will then be specifically defined in the appended claims.

In the accompanying drawing forming a 35 material part of this invention:—

Figure 1—is a top plan view of a game-board constructed according to my invention.

Figure 2—is a perspective view of one of the removable guards.

40 Figure 3—is an end view of the board partly in section.

Figure 4—is an inner side elevation of one of the guards, and

45 Figure 5—is a plan view of two additional removable guards used with my board.

As illustrated on the drawing a board 10, of any desired suitable material and dimensions is provided with a plurality of depressions 11, arranged in alternating rows of 50 fours and threes, so that the rows of threes are located in front of the spaces between the depressions in the rows of fours. Each of the depressions 11, is closed at the bottom as at 12, and is numbered by suitable numbers 13, in 55 any consecutive order suiting the particular

game to be played. For the playing of the game, billiard balls or the like, marked in any suitable manner and propelled by a cue or the like, are used and balls, not entering any depressions in the board, are rolling off the same 60 over the metal lined and inclined surface designated 14. The game-board may be used either on a specially constructed table, may be used on any ordinary table suitable for the purposes in view, or may also be used on a 65 pool or billiard table. In order to limit the movements of the balls, the board is provided at one side edge thereof with a guard 15, projecting with its upper edge over the edge of or out of the plane of the board proper and provided at one of its end edges with a pin 16, 70 adapted to enter a suitable hole in the edge of the board, while a plurality of holes 17, in the guard are adapted for the reception of pins or the like projecting from the side edges of the 75 board, and entering the holes 17, to frictionally connect and hold the guard to the board. The end edges and the side edge opposite to the guard 15, may be also provided with suitable guards 18 and 19, respectively, which at 80 their meeting edges are connected by a hinge 20, or the like, and the inner faces of guards 18 and 19, are equipped with projecting pins 21 and 22 respectively, adapted to enter suitable openings in the end or the side edge of 85 the board.

As shown in Figure 3, the corner depression 11, is formed within a block 23, adapted to slide out and into the board proper in order to allow an exchange of the block and its depression for repairs or exchange of the numbers. A finger hold 24, facilitates the operation of said block. This part is also provided with an upstanding guard 25, projecting 90 above the plane of the game-board and is used when guards, 18 and 19, are dispensed with.

It will be clear that any of the marginal depressions may be located in such a block 23, in order to allow a quick exchange of numbers and for repairing purposes.

100 The operation of my board will be readily understood from the above description without further explanation and it is to be understood that while I have shown and described as one example only of the many ways in which my game-board may be constructed in practice, the preferred form thereof, I do not wish to limit myself to the specific construction disclosed but desire to reserve my right to make such changes as come within the 105 110

scope of the appended claims without departure from the spirit of my invention and the principles involved.

Having thus described my invention what 5 I claim as new and desire to secure by Letters Patent is:—

1. A game-board comprising a plurality of depressed parts formed in said board, an exchangeable means for limiting the run of 10 balls propelled onto said board, a means for allowing a ready exchange of one and the other of said depressed parts, and a runway for the balls leaving the board.

2. A game-board comprising a plurality of 15 depressions of approximately semi-spherical form and closed at the bottom formed in said board, each of said depressions being numbered, a side-guard removably held to one side edge of said board, a means for allowing 20 a ready exchange of any one of said depressions, and a metal-covered runway for the balls failing to enter any of said depressions and leaving the board.

3. A game-board comprising a plate having 25 a plurality of cup-shaped depressions formed therein, closed at the bottom, and arranged in alternating rows of even and odd numbers, a plurality of guard members extending upward beyond the plane of the 30 board, removably secured on the edges of said board, two of said guards hinged together at their meeting ends, a means for removably

and exchangeably holding one of the depressed corner parts to said board, and a metal runway at one edge of said board not 35 protected by said guards, for facilitating the running off of balls not entering the depressions.

4. A game-board comprising a base plate having a plurality of substantially cup 40 shaped depressions formed therein, each closed at the bottom and each provided with a certain number, the depressions arranged in rows of even and odd numbers, the depressions of odd numbers arranged in front of the 45 intervals between each two depressions of even number, a plurality of removable guards, one of said depressions exchangeable, and an inclined metal lined runway at one end of the board for facilitating the running 50 off of balls not caught in said depressions.

5. In a game-board of the class described the combination of a board provided with a plurality of cup-shaped depressions formed therein, a corner block having a depression 55 formed therein, removably and exchangeably held in said board and provided with a finger hold, and a guard for preventing a ball not entering said corner block depression from running off the board.

Signed at New York in the county of New York and State of New York this 23rd day of September A. D. 1927.

HARRY SCHLESINGER.
